UNITED STATES PATENT OFFICE

1,953,532

CURTAIN STRETCHER

Isaiah Creel, New Castle, Pa.

Application May 27, 1933, Serial No. 673,256

5 Claims. (Cl. 45—24)

Among the objects which I have in view are the following.

The provision of a curtain stretcher with flush ends which will be convenient to erect and which will be sturdy and substantially rigid when extended or erected for use, maintaining rectangular corners and which will have no protruding portions likely to catch on the clothes or otherwise cause inconvenience or damage.

10 The provision of a curtain stretcher which when not in use may be conveniently folded up into small compass for storage or for transportation.

15 The provision of a curtain stretcher which can be conveniently and quickly adjusted by the housewife to suit different widths and lengths of curtains.

20 The provision of a new and improved character of adjustable intermediate bar for the curtain stretcher.

25 Other objects will appear from the following description.

In the accompanying drawing wherein I have illustrated practical embodiments of the principles of my invention, Fig. 1 is a broken front elevation of a curtain stretcher in its extended form ready for use.

30 Fig. 2 is a broken end view of the same showing one of the supporting legs and its brace.

Fig. 3 is a rear elevation on enlarged scale showing the construction of one of the top corners, the top rail and post being shown in their extended relation in solid lines and the post being shown folded relative to the rail in dotted lines.

35 Fig. 4 is a sectional detail of the corner structure taken on a plane parallel to that of Fig. 3.

Fig. 5 is a broken front elevation showing the hinge structure which unites the two parts of one of the horizontal rails of the curtain stretcher.

40 Fig. 6 is a rear elevation of the same.

Fig. 7 is a sectional view taken along the irregular line 7—7 in Fig. 5.

45 Fig. 8 is a broken elevation showing one end of the lower horizontal rail and illustrating the means for connecting it to the corresponding post.

Fig. 9 is a broken front elevation of the adjustable intermediate bar with all but one of the pin blocks removed.

Fig. 10 is a broken side elevation of the same.

50 Fig. 11 is a cross sectional view taken along the line 11—11 in Fig. 9.

Fig. 12 is a cross sectional view showing one of the pin blocks.

55 Referring to the drawing, the curtain stretcher comprises two vertical posts 1; a top horizontal

60 rail formed of two parts, 2a and 2b, which rail is hinged at its ends to the tops of the posts 1 and whose parts are hinged together at the center as shown; a bottom horizontal rail also composed of two parts, 3a and 3b, which are hinged together at the center and are provided with means for connecting their outer ends at the desired elevation to the posts 1, and an adjustable intermediate bar 4. The posts and two horizontal rails are provided on their front surface with 65 the usual pins 5 spaced at regular intervals, usually on one inch centers.

For general domestic use, the posts are preferably approximately six feet in length and the two-part rails about eight feet long. The intermediate bar may be about five feet in length. These dimensions may be varied to suit different uses. The elements described are preferably but not necessarily made of wood.

70 The posts 1 are provided with supporting legs 7 whose upper ends are pivoted to brackets 8 extending rearwardly from the posts 1. 8 represents metal braces pivoted to the brackets 9 on the posts 1 and provided with a longitudinally disposed slot 10 through which extends the bolts 80 11 protruding from the leg. 11a represents a nut on the bolt. Thus the legs 6 may be adjusted to give the correct angle to the stretcher and the nuts 11a are then tightened against the braces 8, thus holding the structure rigid. The legs are 85 folded against the posts when the stretcher is not in use.

85 The top corner construction of the stretcher is substantially as shown in Figs. 3 and 4, the top rail and the post being provided respectively with 90 angular plates 12 secured as by screws to their rear faces and having their free ends projecting inwardly as shown and overlapping and pivotally connected together as by the pin 13. When extended in rectangular relation as shown in solid lines in Fig. 3 and also as shown in Fig. 4, the end of the top bar member rests on and is supported by the squared top of the post, and when the stretcher is folded up the two elements are swung so that they are parallel as indicated by the post 100 shown in dotted lines in Fig. 3.

It is very important to solidly brace the elements when they are in their extended relation so that their mutual rectangular relation may be maintained and the corner may be held rigid. 105 I insure this by providing the flat metal rectangular bracket 14 which is secured to the top edge of the top rail as by screws, and which fits on the top surface and the end surface of the top rail and extends beyond the latter sufficiently to over- 110

lap the upper vertical face of the leg 1 when the same is in its extended position, as clearly indicated in Figs. 3 and 4. 15 is a relatively long bolt fixed to and extending outwardly from the post 5. 1 and the free end of the bracket 14 is slotted as at 16 so that when the members are moved into their extended relation the bifurcated end of the bracket straddles the bolt 15 which occupies the slot 16. 17 is a nut on said bolt which is 10 then tightened up snugly against the outer surface of the bracket 14, thus clamping the elements rigidly together in their extended relation and also insuring a rectangular corner for the stretcher. When the stretcher is to be folded up 15 the nuts 17 are loosened and run out on the bolts 15 so that when the elements are folded the free end of the bracket 14 will clear the nut.

I prefer to extend the plate 12 of the post up beyond the upper end of the latter, as shown in 20 Fig. 3, thus bracing the end of the top rail from the rear when the stretcher is erected for use.

As has already been stated, the upper and lower horizontal rails are each formed of two parts which are hinged together at the center. 25 As the hinge structure may be the same in the case of both rails, I will describe that of the top rail in connection with the showing in Figs. 5, 6 and 7. As shown in said figures the two members 2a and 2b have squared ends arranged to abut in 30 flat surface contact when the members are alined. One of said members, 2a, has secured thereto an angular metal bracket 18 which has a portion which fits against the rear face of the member 2a and is secured thereto as by screws.

35 Said bracket extends beyond the end of the member 2a, as clearly shown in Fig. 6 and is provided with a rectangular trough flange 19 at its lower edge which embraces the lower edge of the member 2a and likewise receives the lower edge 40 of the member 2b when the two members are alined, as best shown in Fig. 7. The bracket 18 is extended above the top edge of the member 2a. Attached to the rear face of the member 2b, as by screws, is the angular bracket 20 which extends forwardly past the end of the member 2b 45 to overlap the bracket 18, the extended portion of the bracket 20 being offset outwardly so as to clear the bracket 18 and to fit snugly against this outer surface. The bracket 20 is also extended above 50 the top edge of the element 2b and 21 is a hinge pin which engages registering holes in the two brackets so as to connect the parts 2a and 2b in hinged relation.

22 is a relatively long bolt which is fixed to and 55 protrudes from the lower edge of the element 2b adjacent to its hinged end and the flange 19 of the bracket 18 has its outer end slotted, as indicated at 23, so that the bracket 18 may straddle the bolt 22 when the parts 2a and 2b are alined. 60 24 is a nut on the bolt 22 which may be tightened up against the flange 19, thus clamping the parts 2a and 2b rigidly in their alined relation.

When the stretcher is to be folded up, the nut 65 24 is backed away so that the part 2b may be swung counterclockwise in Fig. 5 and clockwise in Fig. 6 into substantial parallelism to the part 2a.

I have shown the nut 17 as a wing nut and the 70 nut 24 as a cylindrical knurled nut but it will be understood that either or any other suitable type of nut may be used.

The ends of the lower horizontal rail 3a-3b are each provided with rectangular brackets 25 attached as by screws to the rear face of the rail 75 member and extending on beyond the same so

that its rectangular bent end 26 forms with the end of the bar member a three sided socket 27 in which may fit the corresponding post 1. The flange 26 is provided with a threaded hole in which is mounted the thumb bolt 28 which has an enlarged inner end so that when the post 1 occupies the socket 27 the bolt 28 may be screwed up tightly against the post, thus clamping the posts to the lower horizontal rail at each end of the latter.

It is obvious from the foregoing that the curtain stretcher may be quickly set up from its folded state and fixed in its extended condition with its angles true rectangles and with its parts held in rigid relation to each other, and also that the lower horizontal rail may be quickly detached from the stretcher and folded and the legs may be unclamped from the top rail and may be folded against the same and the two parts of the top rail may be folded together, enabling the stretcher to be packed away in small compass.

Referring now to Figs. 8 to 11 inclusive, the vertical intermediate bar 4 is formed of a metal plate having a channel shaped cross section with the walls of the channel outwardly converging as 100 best illustrated in Fig. 11. The upper end of the channel bar 4 is provided with a rectangularly bent bracket 29 which is of proper size and shape to hook snugly over the top rail as shown in Fig. 1. The lower end of the bar 4 is provided with 105 a horizontal flange 30 having a threaded hole in which is screwed the thumb nut 31 having an enlarged upper end.

Mounted in the channel of the bar 4 are a plurality of blocks 32 having base portions of proper 110 shape to be slidably held in the channel of the bar 4 and to be prevented from outward displacement therefrom. The arrangement is such that the channel or bar 4 is provided with sufficient of the blocks 32 that when the blocks 115 are spread at any point to admit one of the members 3a or 3b of the lower rail the channel will be nearly filled from top to bottom. Then the thumb bolt 31 is screwed upwardly and tightened against the lower block, thus forcing the lower 120 blocks upwardly against the lower rail and clamping the latter between the adjacent blocks, and also by upward pressure of the top block clamping the intermediate bar 4 tightly to the top rail.

Each of the blocks 32 is provided with a pin 125 5 at its center and the blocks are of such dimensions that the distance between the pins of abutting blocks is equal to that between adjacent pins on the posts and rails. Thus if the latter distance be one inch, the blocks would be made an 130 inch in vertical dimension, thus giving an inch space between the pins of adjacent blocks. Again by setting the pins on the top rail half an inch from its lower edge, and those on the bottom rail half an inch from its upper edge, the pins on the intermediate bar will be properly located relative to those on the rails so that the pins will always be properly located for engaging the curtain or curtains to be stretched regardless of the effective dimension to which the stretcher is adjusted. 135 Thus the bottom rail is arranged to be raised or lowered the space of one inch or multiples thereof and consequently the distance between any pin on the stretcher and any other pin is always an inch or multiples thereof.

It is apparent that curtains of any width and length within the limits of the stretcher's range of adjustment may be properly stretched inasmuch as the capacity of the stretcher may be regulated to properly fit the particular size of cur- 140 145 150

- tain. Again my improved construction insures perfectly rectangular corners and corner rigidity so that the stretched curtains are perfectly square and uniformly stretched throughout.
- 5 The stretcher may be quickly erected and adjusted for use and as quickly folded up into small compass for storage or transportation. It is simple and inexpensive of construction and extremely durable.
- 10 I claim:—
1. In a foldable curtain stretcher, the combination with a pair of posts and a top rail and a bottom rail connecting the posts, the bottom rail being adjustable vertically on the posts, of an intermediate vertical member arranged to connect said rails and adjustable along the same, said member comprising a bar, a plurality of pin blocks mounted on said bar and slidably longitudinally thereof, said pin blocks being arranged to be separated at the proper level to receive between them the bottom rail, and means for applying pressure to said blocks longitudinally of the bar to clamp the rail to said member.
  2. In a foldable curtain stretcher, the combination with a pair of posts and a top rail and a bottom rail connecting the posts, the bottom rail being adjustable vertically on the posts, said posts and rails being provided with curtain-anchoring pins on their front faces, of an intermediate vertical member arranged to connect the rails and adjustable along the same, said member comprising a back bar of channel cross-sectional shape and a plurality of pin-blocks slidably mounted in the channel, said pin blocks being of proper width whereby the pins are properly placed to receive the edge of the curtain, said blocks being arranged to be separated at the proper level to receive the bottom bar between them, and means for forcing the blocks longitudinally of the bar to clamp the rail stationary between adjacent blocks.
  3. In a foldable curtain stretcher, the combination with a pair of posts and a top rail and a bottom rail connecting the posts, the bottom rail being adjustable vertically on the posts, said posts and rails being provided with curtain-anchoring pins on their front faces, of an intermediate vertical member arranged to connect the rails and adjustable along the same, said member comprising a back bar of channel cross-sectional shape and provided at one end with a hook to fit over the top rail and at the other end with an abutment member, a plurality of pin blocks slidably mounted in the channel, the blocks being arranged to be separated at the proper level to receive the bottom rail between adjacent blocks, and the abutment member being forced upwardly against the lowermost block to clamp the bottom rail to the member and to clamp the top hook fixedly to the top rail.
  4. A curtain stretcher element comprising a metal bar of channel cross sectional shape, said channel having outwardly converging walls, a plurality of pin-blocks mounted in the channel and slidable longitudinally of said element, and an adjustable abutment member arranged to apply pressure to said blocks longitudinally of said element for the purpose described.
  5. A curtain stretcher element comprising a metal bar of channel cross sectional shape, said channel having outwardly converging walls, a plurality of pin-blocks mounted in the channel and slidable longitudinally of said element, means for limiting the movement of said blocks toward one end of said element, and an adjustable abutment member at the other end of said member to apply pressure to said blocks longitudinally of said member.
